UNITED STATES PATENT OFFICE.

EDWARD L. MARSHALL AND GEORGE P. PAVLIK, OF RUTH, NEBRASKA.

WRENCH.

1,005,724.

Specification of Letters Patent. Patented Oct. 10, 1911.

Application filed June 8, 1911. Serial No. 631,970.

To all whom it may concern:

Be it known that we, EDWARD L. MARSHALL and GEORGE P. PAVLIK, citizens of the United States, and residents of Ruth, in the county of Knox, State of Nebraska, have invented a new and useful Improvement in Wrenches, of which the following is a specification.

Our invention is an improvement in wrenches, and has for its object the provision of a simple, compact, convenient wrench of the alligator type, comprising a handle, a fixed, and a movable jaw, and having means for moving the movable jaw toward and from the fixed jaw, and for locking it in adjusted position.

In the drawings: Figure 1 is a plan view of the improvement; Fig. 2 is an enlarged plan view of one end of the improvement with the cover plate removed; Fig. 3 is a plan view of one jaw; Fig. 4 is a section on the line 4—4 of Fig. 2; and Fig. 5 is a perspective view of the locking bar.

The present embodiment of the invention comprises a shank 1 formed into a grip at one end, and having the other end enlarged at 2, and formed into a jaw 3 on the opposite side of the enlargement from the grip. The enlargement 2 is substantially rectangular in cross section and is recessed on one face at 4, the recess being substantially rectangular as shown, and opening into a recess 5 substantially circular in cross section at the end of the said enlargement. The enlargement 35 is transversely perforated at the center of the recess 5, as indicated at 6, and a boss or hub 7 encircles the perforation or opening in the recess. An arc-shaped rib 8 is provided between the recesses 4 and 5 of approximately the same height as the boss, and the rib is formed on a circle having its center at the center of the recess.

The jaw 3 is the fixed jaw of the wrench, and the movable jaw 9 is provided at its inner end with an enlargement 10 filling the recess 5. At the center of the recess the jaw is perforated at 11 and counterbored at 12 around the perforation or opening to receive the boss or hub 7. A pin 13 provided at one end with a head 14 and at the other with a transverse opening 15 is passed through the registering openings 6 and 11, and is held in place by the head, and a pin 16 passed through the opening 15.

The jaw 9 is provided with an extension 17 on the opposite side of the enlargement and

extending substantially radially therefrom, and the outer face of the extension and the outer face of the enlargement are grooved at 18, the groove extending radially to the pin 13 and being enlarged laterally on both sides at its inner end, as indicated at 19.

A bar 20 is seated in the groove 18 and is provided with a head 21 at its inner end, fitting the enlarged end 19 of the groove. The outer end of the groove 17 is deepened, as indicated at 22 in Fig. 4, and a coil spring 23 is seated in the said portion between the extension 17 and the end of the bar. The bar 20 extends beyond the end of the extension and is provided with an outwardly extending lug 24. A cover plate 25 is seated on the enlargements 2 of the shank and 10 of the movable jaw and is held in place by screws 26. The plate is provided with an opening for receiving the pin 13 and the head 14 of the pin engages the outer face of the plate. The plate is also provided with an arc-shaped slot 27 near the opposite end from the pin 13, and the bar 20 is provided with a threaded recess 28 registering with the slot. The slot 27 is formed with the pin 13 as a center, and a screw 29 is passed through the slot and engages the threaded opening 28. The plate 25 is provided with an arc-shaped series of openings 30 adjacent to the slot 27 for receiving the pin 24 on the bar 20.

The wrench is assembled by placing the fixed jaw on the shank with the bar 20 and spring 23 in place, and the cover plate 25 is arranged over the enlargements and secured in place by the screws 26. The pin 13 is then placed and the pin 16 is inserted. The set-screw 29 is then placed in position and the wrench is ready for use. In using the wrench the jaw 9 is operated by means of the screw 29. It will be noticed that the end of the groove 18 remote from the pin 13 is beveled, as indicated at 31 in Fig. 4, so that the bar 20, which is the locking bar, may rock in the groove. The portion 21 of the bar is also beveled, as indicated at 32, for the same purpose. When the bar is rocked by depressing the head of the screw 29, the lug 24 may be disengaged from the openings 30 to permit the movable jaw to be swung on the pivot pin 13 to open or close the jaws. When the bar is released, the jaw is held in adjusted position.

We claim:

1. A wrench comprising a handle pro-

- vided at one end with an integral jaw, and with a lateral enlargement between the jaw and the handle, said enlargement being recessed on one face, a movable jaw having a lateral enlargement fitting the enlargement of the handle and pivoted thereto, said movable jaw having an extension on the opposite side of the enlargement, said extension being received in the recess of the handle and being provided with a longitudinal groove on its outer face, a locking bar in the groove, the bottom of the groove being beveled at the outer end to permit the bar to rock, a spring between the outer end of the bar and the bottom of the groove, said bar having a lug on its outer face adjacent to the spring, a cover plate secured over the recess and having an arc-shaped series of openings for engagement by the lug to hold the movable jaw in adjusted position, said plate having an arc-shaped slot adjacent to the series of openings, and a set-screw passing through the slot and engaging the locking bar.
- 25 2. A wrench comprising a handle provided at one end with an integral jaw, and with a lateral enlargement between the jaw and the handle, said enlargement being recessed on one face, a movable jaw having a lateral enlargement fitting the enlargement of the handle and pivoted thereto, said movable jaw having an extension on the opposite side of the enlargement, said extension being received in the recess of the handle and being provided with a longitudinal groove on its outer face, a locking bar in the groove, the bottom of the groove being beveled at the outer end to permit the bar to rock, a spring between the outer end of the bar and the bottom of the groove, said bar having a lug on its outer face adjacent to the spring, a cover plate secured over the recess and having an arc-shaped series of openings for engagement by the lug to hold the movable jaw in adjusted position, said plate having an arc-shaped slot adjacent to the series of openings, and a set-screw passing through the slot and engaging the locking bar.
- 30 3. A wrench comprising a handle having a fixed jaw at one end, said handle being recessed adjacent to the jaw in one face, a movable jaw pivoted in the recess and extending alongside the fixed jaw, said jaw having an extension in the recess on the opposite side of the pivotal connection, said extension having a longitudinal groove, a cover plate over the recess, a locking bar in the groove mounted to rock toward and from the said plate and provided with a lug on the face adjacent to the plate, said plate having spaced openings for receiving the lug to hold the movable jaw in adjusted position, a spring engaging the bar for holding the lug in engagement with the openings, said plate having a transverse slot adjacent to the openings, and a screw passing through the slot and engaging the bar to rock the same and swing it laterally.
- 35 4. A wrench comprising a handle having a fixed jaw at one end, said handle being recessed adjacent to the jaw in one face, a movable jaw pivoted in the recess and extending alongside the fixed jaw, said jaw having an extension in the recess on the opposite side of the pivotal connection, said extension having a longitudinal groove, a cover plate over the recess, a locking bar in the groove mounted to rock toward and from the said plate and provided with a lug on the face adjacent to the plate, said plate having spaced openings for receiving the lug to hold the movable jaw in adjusted position, a spring engaging the bar for holding the lug in engagement with the openings, and means for rocking the bar and swinging the movable jaw.
